Des. 228,873

Patented Oct. 30, 1973

228,873

FILE HOLDER FOR AUTO BODY WORK

Regent E. Cloutier, 2251 Sandpiper Drive,
Fairfield, Conn. 94533

Filed Jan. 31, 1972, Ser. No. 222,455

Term of patent 14 years

Int. Cl. D8—05

U.S. Cl. D8—94

FIG. 1 is a top plan view of a file holder for auto body work showing my new design;

FIG. 2 is a side elevational view of one side, the opposite side being in mirror symmetry;

FIG. 3 is a bottom plan view;

FIG. 4 is an end elevational view of the left-hand end of FIG. 2; and,

FIG. 5 is an end elevational view of the right-hand end of FIG. 2.

I claim:

The ornamental design for a file holder for auto body work, as shown and described.
